(57) CLAIM

The ornamental design for a desktop game, as shown and described.

DESCRIPTION

FIG. 1 is a top, left, front perspective view of a desktop game showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a cross-sectional view taken along line 8-8 of FIG. 2.

The broken lines shown in the drawings depict portions of the desktop game that form no part of the claimed design.
